UNITED STATES PATENT OFFICE.

HYMAN LEVINE, OF DENVER, COLORADO, ASSIGNEE TO INGERSOLL-RAND COMPANY, OF JERSEY CITY, NEW JERSEY, A CORPORATION OF NEW JERSEY.

SHANK AND BIT PUNCH.

Application filed July 3, 1925. Serial No. 41,270.

This invention relates to shank and bit punches, but more particularly to that type of machine in which the punch pin is both hammered into and out of the drill steel.

5 The objects of the invention are to enable a variable stroke hammer to be used and automatically vary the length of the stroke of the hammer in accordance with the direction in which the pin is to be driven. When 10 the pin is being driven out of the steel, the hammer stroke is automatically lengthened so that the hammer is permitted to strike the back head and the blows are transmitted to the front head and anvil block 15 through the side rods.

The invention is shown in one of its preferred forms in the accompanying drawings, in which

20 Figure 1 is a longitudinal sectional side elevation of the machine,

Figure 2 is a similar view with the piston in a different position,

25 Figure 3 is a similar view showing the pin being driven out of the drill steel, and

Figure 4 is a longitudinal sectional plan view on the line 4-4 of Figure 3 looking in the direction of the arrows.

Referring to the drawings, the hammer cylinder A, to which may be connected the 30 pressure fluid feed cylinder B, is conveniently mounted on the slide or guide C and the piston rod D of the feed piston E is connected to the frame F. The drill steel G is held in any suitable clamping device 35 or jaws H and J which may be the clamping jaws on the usual drill sharpener. The front head K and back head L of the hammer cylinder are connected by the usual side rods O and the front head K is recessed at P to receive the head Q of the anvil block R. A cap or cover S is provided for the front head and the pin T is held in the anvil block as by means of the 40 key U. In the position of the parts shown 45 in Figure 1, the striking portion V of the anvil block extends into the cylinder in the path of the piston W which in this instance is shown as a differential valveless piston having the head X, the neck Y and a rearward reduced extension having a rearward face Z.

A throttle valve α controls both the distribution of motive fluid to the hammer cylinder and to the feed cylinder B by means 50 of suitable ports and passages. In the posi-

tion of the valve α in Figures 1 and 2, pressure fluid entering through the central portion b of the valve passes through the passage c in the cylinder to the rearward pressure surface Z of the piston W and during 60 the operation of the piston, constant pressure is supplied to the rearward face Z. Pressure fluid is also supplied around the piston neck Y to the rearward face d of the piston head X to drive the piston forward and the forward end of the cylinder is exhausted through the exhaust port e. When the rearward end Z of the piston overruns the passage f, pressure fluid is supplied 65 to the forward end of the piston to drive it 70 rearwardly, and in Figure 2 the piston is shown moving rearwardly.

Pressure fluid is also supplied through the passage g to the forward end of the feed cylinder B and the rearward end of the 75 feed cylinder B is exhausted to the passage h and to atmosphere through the port j in the valve α .

While the hammer piston W is imparting 80 blows of impact to the anvil block R to drive the pin into the drill steel, the compression relief passage k leading from the rearward end of the enlarged bore of the cylinder to the front head K is closed at its 85 forward end because the head Q of the anvil block closes the port o in the front head which affords communication between the relief passage k and the chamber or recess P in the front head, which chamber is vented to atmosphere at the port p. There is thus 90 sufficient compression behind the enlarged head X of the piston W on its rearward stroke to prevent the rearward end Z of the piston from striking the back head L. The compression behind the piston head X 95 shortens the piston stroke automatically and prevents blows of impact being delivered by the piston to any part of the cylinder or back head, although the full force of the impact blow of the piston is delivered on 100 the forward stroke upon the anvil block.

The throttle valve α is turned to the position indicated in Figure 3 in order to retract the machine and drive the pin out of the drill steel. Pressure fluid will be admitted through the passage h to the rearward end of the feed cylinder B and the forward end of the feed cylinder will be exhausted to atmosphere through the passage g and through the port q in the valve 110

a. Pressure fluid is supplied to the hammer cylinder for the operation of the hammer as before. In retracting the machine, the anvil block R has been moved forwardly in 5 the recess P in the front head K, thus removing the anvil block head Q from the port o in the front head and connecting the compression relief passage k with atmosphere through the atmospheric port p in the 10 front head. In such case, the compression behind the enlarged head X of the piston W is relieved to a sufficient extent to permit the rear end Z of the piston to strike against the back head L of the cylinder and thus 15 transmit blows through the back head and side rods O to the front head K and thence to the anvil block R to drive the pin out of the drill steel.

The stroke of the piston is automatically 20 shortened or lengthened in accordance with the direction in which the pin is to be driven.

I claim:

1. In a shank and bit punch for drill steels, the combination of means for holding 25 the drill steel, a hammer cylinder, an anvil block mounted in said cylinder, a pin carried by the anvil block and adapted to enter the drill steel, a variable stroke fluid actuated hammer piston reciprocating in 30 the cylinder, and means for automatically varying the length of the stroke of the hammer in accordance with the direction in which the pin is to be driven.

2. In a shank and bit punch for drill 35 steels, the combination of means for holding the drill steel, a hammer cylinder, an anvil block mounted in said cylinder, a pin carried by the anvil block and adapted to enter the drill steel, a variable stroke fluid

actuated hammer piston reciprocating in 40 the cylinder, and means for automatically lengthening the stroke of the hammer for driving the pin out of the drill steel.

3. In a shank and bit punch for drill 45 steels, the combination of means for holding the drill steel, a hammer cylinder, an anvil block mounted in said cylinder, a pin carried by the anvil block and adapted to enter the drill steel, a variable stroke fluid actuated hammer piston reciprocating in the 50 cylinder, cushioning means for preventing the hammer from striking the back head of the cylinder when the pin is being driven into the drill steel, and means for automatically relieving said cushion to a sufficient 55 extent to lengthen the hammer stroke and permit the hammer to strike the back head when the pin is being driven out of the drill steel.

4. In a shank and bit punch for drill 60 steels, the combination of means for holding the drill steel, a hammer cylinder, an anvil block mounted in said cylinder, a pin carried by the anvil block and adapted to enter the drill steel, a variable stroke fluid 65 actuated differential valveless hammer piston reciprocating in the cylinder, cushioning means for preventing the hammer from striking the back head of the cylinder when the pin is being driven into the drill steel, 70 and means for automatically relieving said cushion to a sufficient extent to lengthen the hammer stroke and permit the hammer to strike the back head when the pin is being driven out of the drill steel. 75

In testimony whereof I have signed this specification.

HYMAN LEVINE.
